(57) **CLAIM**

The ornamental design for a power collection fuse box, as shown and described.

DESCRIPTION

FIG. 1 is a perspective view of a power collection fuse box, showing our new design;

FIG. 2 is a front view thereof;

FIG. 3 is a right side view thereof, the left side being symmetrical;

FIG. 4 is a top view thereof;

FIG. 5 is a rear view thereof;

FIG. 6 is a bottom view thereof;

FIG. 7 is a cross sectional view thereof, taken along the line 7-7 in FIG. 2; and,

FIG. 8 is a cross sectional view thereof, taken along the line 8-8 in FIG. 2.

The broken lines show portions of the power collection fuse box that form no part of the claimed design.

1 Claim, 8 Drawing Sheets
